UNITED STATES PATENT OFFICE.

EDWIN KELLER, OF ZURICH, SWITZERLAND.

LETTERING-GUIDE.

1,285,213.

Specification of Letters Patent. Patented Nov. 19, 1918.

Application filed October 26, 1917. Serial No. 198,606.

To all whom it may concern:

Be it known that I, EDWIN KELLER, a citizen of the Swiss Confederation, and residing at Zurich, Switzerland, have invented 5 certain new and useful Improvements in Lettering-Guides, of which the following is a specification.

The present invention relates to a novel device for rapidly and correctly producing 10 sign writing and the like by means of lettering guides, and the invention essentially consists in the particular construction, combination and coöperation of parts, as will now be fully described in connection with 15 the accompanying drawings, in which Figure 1 shows a plan view of the complete device; Fig. 2 represents a section on line C—D of Fig. 1, and Fig. 3 a similar section on line A—B; Fig. 4 shows a section on line 20 G—H of Fig. 2; Fig. 5 represents a fragmental view of a lettering guide with the stylus point in operative position.

The frame is composed of the longitudinal members 1 and 2, and the cross-members 3 and 25 4; supported on the swiveled rollers 5 (Figs. 1 and 3), and can thus easily be moved about over the surface to be written upon without damage to the latter. Pointed thumb screws 6 in the cross member 3 serve to fix the 30 frame in the desired position on the writing surface, and the cross-members 3, 4 are provided, intermediate their extremities, with hinges 7 for folding up the frame when not in use. The longitudinal frame members 1, 35 2 are provided with slots 8 (Fig. 1) in which operate the screw bolts 10, which have a square portion 9 and which can be tightened on the respective longitudinal members by manipulation of their nuts 12. The sliding bars 11, which extend parallel to the 40 cross-members 3, 4, are provided in their angularly bent-off extremities with holes through which pass the set screws 10. Just within the bent extremities these sliding 45 bars are provided with holes for receiving the screw bolts 13 (Fig. 2) with heads 14. A clamping bar 15 is provided for each sliding bar and the two bars, termed clamping member, are operatively connected by the 50 screws 13. Lettering guides 17 (Figs. 1, 2 and 4), in which a pattern, letters, numerals, or other characters are cut through, are to be inserted in between these two bars and are then clamped fast by tightening the 55 screws 13. The lettering guides 17 are angu-

larly bent or stepped near their one extremity and are then formed into a handle, in such manner that between the stencil portion proper and the handle a flat portion is presented of the width of the clamping 60 member, as shown in Fig. 9. The sliding bars are provided with scales to facilitate the positioning of the stencil plates.

To the lower cross-member 4 is fixed a 65 socket 18 into which the stylus is to be inserted during the filling operation, so that also one-armed operators can readily fill the stylographic pen with the writing fluid.

In operation the frame is placed onto the writing surface and is secured thereon 70 against inadvertent displacement by screwing down the pointed screws 6; the nuts 16 are eased, the letter guides are successively inserted in between the two bars 11 and 15, 75 are correctly positioned by the aid of the scales, and are finally clamped between the bars by tightening the nuts 16.

Depending upon the inscriptions or other representations to be produced the sliding 80 clamping members are shifted up or down within the frame and are finally locked in position by the nuts 12. Scales on the longitudinal members 1, 2 facilitate the positioning of the individual clamping members. A stylus 22 is inserted into the cut-outs in the 85 lettering guides to produce their counterparts on the underlying writing surface.

The described invention enables an unskilled writer and even a one-armed one to turn out quick and accurate work. 90

What I claim is:—

1. In a device of the class described, the combination of a frame comprising longitudinal members and sectional transverse members, hinges connecting the respective 95 sections of each transverse member, the longitudinal members having slots, means for positioning the frame, bars extending over the longitudinal members, means extending through the slots for securing the bars to the longitudinal members, clamps extending over the face of each bar, means for fastening the clamps to the bars, and a plurality of lettering guides interposed between the bars and the clamps, each guide 100 having an offset portion to receive the bar and bent at one end to form a handle.

2. In a device of the class described, the combination of a frame formed with longitudinal slots, bars extending across the 110

frame, clamping means extending through the slots to secure the bars in position, rollers on the frame, screws extending through the frame to fasten the same to a support, 5 clamps fitted on the faces of the bars, lettering guides interposed between the latter clamps and the bars, the guides having transverse seats to receive the bars when the clamps are tightened.

3. In a device of the class described, the combination of a frame formed with longitudinal slots, bars extending across the frame, screws engaging the slots for ad-

justably mounting the bars, the frame having scales adjacent the slots, a clamp extending across the face of each bar, means for adjustably securing the clamps, each clamp having a scale on its face on each side of a medial line, and lettering guides interposed between its clamps and the bars, each 15 guide having a seat to receive the bars, the guides extending beyond the bars.

In witness whereof I have hereunto set my name.

EDWIN KELLER.
